UNITED STATES PATENT OFFICE.

WILLIAM L. HAYES, OF CLEVELAND, OHIO.

PUNCH-GRINDING MACHINE.

SPECIFICATION forming part of Letters Patent No. 274,322, dated March 20, 1883.

Application filed January 8, 1883. (No model.)

To all whom it may concern:

Be it known that I, WILLIAM L. HAYES, a citizen of the United States, residing at Cleveland, county of Cuyahoga, State of Ohio, have invented or discovered a new and useful improvement in Punch-Grinding Machines; and I do hereby declare the following to be a full, clear, concise, and exact description thereof, reference being had to the accompanying drawings, making a part of this specification, in which—like letters indicating like parts—

Figure 1, Sheet 1, is a top plan view of my improved punch-grinding machine. Fig. 2 is a vertical sectional view, partly in elevation, the plane of section being taken in the plane of the line xx , Fig. 1. Fig. 3, Sheet 2, is a vertical sectional view taken in the plane of the line yy , Fig. 1; and Fig. 4 is a similar view taken in the plane of the line zz , Fig. 1.

In the preparation of die-plates for wire-drawing it is customary to make use of punches which are carefully ground with a long and gradually-tapering point, with which the die-opening is shaped and fitted. In order to secure the desired accuracy of die-opening, it is requisite that the punch should be made round and of uniform straight taper.

The purpose of my invention is to provide adjustable mechanism for holding and rotating the punch to be ground, thereby dispensing with the hand skill heretofore required, and also securing more uniform and perfect work.

In general terms my invention may be stated to consist of certain combinations of a rotary chuck for holding a punch adjustable in angle and position with relation to the periphery of the stone, and also movable across the grinding-face of the stone, with gear mechanism for giving rotary motion to the chuck, and adjustable or sliding frame-supports for effecting the desired adjustments, as hereinafter more fully described and claimed.

In the drawings I have illustrated a rotary grindstone by a small segment, A, which is mounted in the usual way upon a frame or support, a portion of which is shown at A'.

The punch P is held in a chuck, C, which may be of any suitable or well-known construction, adapted to grasp and hold the punch in line with its axis. Extending downward from the chuck is a shaft or arbor, C', having a conical enlargement, c', tapering downward toward

the reduced central bearing, c. Upon the lower end of the shaft or arbor is secured a pinion, b, having a conical sleeve-hub, c², which tapers toward the central bearing, c, and forms, in effect, a part of the journal-bearing of the arbor. These parts c c' c² of the arbor are inclosed in an extensible bearing-box, E, which is formed in two parts, e e'. In the base or lower part, e, is formed a conical box, e², adapted to receive the part c² of the arbor, and a straight tubular bearing, e³, for the part c of the arbor. The exterior of box e, at its end adjacent to box e', is turned down, forming a sleeve projection, e⁴, which enters a corresponding socket, e⁵, in the end of e'. The interior of the part e' is bored out, forming a conical box, e⁶, for the other cone, c', of the arbor. The exterior of part e', at its end adjacent to e, is threaded, as at e⁷, and a nut, e⁸, is fitted thereon, which abuts against the shoulder e⁹ on box e. By turning this nut backward on thread e⁷ the two-part boxes e e' will be separated and pressed against the cone-surfaces c' c² to any desired extent, thereby securing a close journal-bearing adapted to exclude water and prevent end motion of the arbor. This is an important feature in securing protection from rust and the desired uniformity of bearing of the punch upon the periphery of the stone. If desired, however, the adjacent faces of sleeve e⁴ and socket e⁵ may be threaded, as in Fig. 4, and screwed together, thereby providing for adjusting the parts of the box upon the bearing of the arbor, and in such case the nut e⁸ may be used as a jam-nut to lock the parts of the box in the desired adjustment.

From either side of the arbor-bearing E two arms, E', extend in opposite directions to and are connected with boxes or collars E², which encircle a shaft, B, which latter is mounted and driven with rotary motion, as presently described. The pivot-connection made with shaft B by the boxes E² permits movement of the chuck and punch to vary the angle of elevation, and thereby set them in a line or direction tangential to the periphery of the stone at whatever distance the pivot-bearings E² may be from the stone. The boxes E² may also be moved along the line of the shaft, whereby the punch may be moved laterally back and forth across the grinding-face of the stone to prevent excessive wear in one place. Rotary motion is given to the chuck and punch

by the bevel-pinion b' gearing with a similar bevel-wheel secured on the end of box-sleeve B' , which latter surrounds shaft B within the box E^2 . Driving-connection is made between the sleeve and shaft by feather and groove, the latter being made in the shaft, as represented at b^3 . The pinion b' is held in position to mesh with gear b between the box E^2 on its back face and a box, d , which encircles the shaft between the front face of such pinion and the opposite box or collar, E^2 . From the box d a web or plate, d' , extends laterally to an enlarged block, D , which is formed with transverse mortise or groove d^3 through it or in its under face, which fits and slides upon the transverse bar or plate i of the part I of the frame.

In the rear of block D is pivoted a drum, D^2 , by pin d^4 . Within this drum is a clock-spring, D^3 , secured at its inner end to pin d^4 and at its outer end to the shell of the drum, as illustrated in Fig. 2, whereby the spring is operative in turning the drum on its pivot, and thereby pressing the punch upon the periphery of the stone, as presently described. From the surface of drum D^2 an arm, D' , is extended upward, and makes adjustable connection with the raised side plate, d^5 , by screw d^6 and curved slot d^7 .

Between the free end of arm D' and the box E is a connecting-rod, H , having pivoted end attachments, as at h' , and being formed in two parts, $h\ h$, which are connected by a coupling-nut, h^2 . The purpose of this connection between the chuck-box and the adjustable arm D' is to provide for setting the chuck and punch at any desired angle of elevation within the range required in use. When this adjustment is determined it may be maintained by binding the arm D' to the slotted plate d^5 by set-screw d^6 ; or, if preferred, the set-screw may be loosened and the spring D^3 be permitted to communicate its pressure to the punch and stone through the connections described; or the desired inclination of the punch may be secured approximately by the adjustment provided for the arm D' , and final accuracy of inclination be secured by lengthening the connecting-rod H by turning the coupling-nut h . In order to effect the transverse movement of the punch across the face of the stone before referred to, the block D may be pushed along the bar or plate i , thereby moving the drum and arm D^2 D' , the box d , gear b' , and boxes or collars E^2 , with the devices connected therewith. This movement may be given by the hand of the attendant or by mechanism, as may be preferred.

The shaft B , which imparts rotary motion to the punch, as before described, is mounted by journal-bearings b^2 , at or near its ends, upon the plate I . This plate is adjustably mounted on the bed-plate N by passing its ends i' into slots n , formed in the raised side pieces, N' , thus permitting movement of plate I upon plate N toward and from the stone. This movement is imparted by a threaded rod, m , which screws

one end into a nut, m' , secured to plate I , and passes at its outer end through an upright plate or flange, n' , raised on the outer edge of bed-plate N . A hand-wheel, m^2 , and collar m^3 prevent endwise movement of the rod. Consequently by its rotation the plate I will be moved back and forth on the plate N .

At right angles to shaft B is mounted a counter-shaft, R , having journal-bearings rr at or near its ends, which are secured to bed-plate N . Between these bearings two arms, i^2 , of plate I diverge from the transverse bar i , and, passing to either side of the line of shaft B , encircle shaft R by boxes i^3 . These box-bearings of plate I on shaft R serve as guides to direct the movement of the plate, and prevent endwise displacement with relation to bed-plate N . On the end of shaft B , between these arms i^2 , is secured a bevel-gear, b^4 , by sleeve-box B^2 . This pinion b^4 intermeshes with a similar gear, r^4 , on shaft R , which latter is held by sleeve-box R' between the box i^3 at its back and the gear b^4 in front. As the plate I , with shaft B , is moved by screw m , the gear r^4 will slide along shaft R , its sleeve and the shaft being connected so as to transmit rotary motion by feather and groove r^2 . The shaft R is driven by bevel-gears r^3 s^3 , the latter being carried on the inner end of a sleeve-box, S' , which is journaled in box-bearing S^3 , secured on the bed N .

Through the axis of sleeve S' is passed a tubular shaft, S , the two having feather-and-groove connection, as at s^2 . The inner end of this shaft is journaled in pillow-block S^5 , and is prevented from being withdrawn in one direction by collar or flange s' . Through the axis of the shaft is passed a spindle, W , having an enlarged head, w , on its inner end, pointed at its extremity, which enters a chamber, s^5 , in the end of shaft S . A spring, w' , is seated around the spindle, between the head and shoulder s , the pressure of which is opposed by a screw-stop, L , secured by nut L' in the upright n^2 . By turning this screw-stop the spindle may be moved longitudinally within the shaft, the screw forcing it in one direction and the spring in the other direction.

Upon the outer end of sleeve S' is a cone-faced disk, S^4 , the inclined face s^4 of which is adapted in size and form to enter and take frictional bearing upon the periphery of a correspondingly-shaped recess, u , made in the adjacent side face of pulley U . This pulley is mounted idle on the end of shaft S . A cap, U' , is screwed on the end of the hub w' of the pulley, within which is inclosed a disk-head, w^2 , removably secured on the end of the spindle. As the spindle is moved by spring w' or by screw L , such movement will be communicated to the pulley by the pressure of head w^2 , thus causing it to make frictional engagement with disk S^4 , or to run idle, as may be desired. By adjusting the stop L this frictional contact may be set with reference to running the apparatus as against any desired degree of resistance within the ordinary requirements of

use, whereby the apparatus may be put into and out of driving-gear, or may be set at proper tension for driving the mechanism with such power only as will permit the attendant to stop it with his hand for changing punches, &c., causing the pulley U to turn on the disk S⁴.

The bed-plate N may be secured rigidly to the frame A' of the stone. I prefer, however, to make an adjustable connection by tongues a and grooves a'. The plate N may thus be set at any desired distance from the periphery of the stone, and it may be bound in such position by set-screws or in any other convenient way.

In operation the plate N is set upon and secured to the frame at the desired point with reference to the size of stone and length of punch to be ground. This setting may, however, be only an approximation to the desired adjustment, and may be determined with reference to grinding punches differing somewhat in size and length, and in such case the final adjustment toward and from the stone is made by moving plate I upon plate N, as before described. By means of these adjustments, and that provided for varying the angle of elevation, before described, the punch may be ground practically with any desired bevel or inclination. The uniform rotary motion imparted, as described, to the punch, will, in connection with the rotation of the stone, secure a practically round point, and a much better one than is ordinarily secured by hand-grinding. The provision made for moving the punch transversely across the face of the stone will preserve a good grinding-face on the latter. The punch may be pressed upon the stone while grinding either by the spring D³ or by hand, bearing upon the chuck-box E. The spring is preferred for this purpose, however, as much more uniform pressure can be secured by it than by hand. The frictional-clutch device shown and described is not claimed herein, as it will be included in the subject-matter of a separate application for patent.

I claim herein as my invention—

1. The combination of chuck C, shaft B, box E, having pivot-connection with the shaft, gears b b', and power mechanism for giving the shaft rotary motion, substantially as set forth.

2. A chuck, C, having an arbor with conical journal-bearings c' c² thereon, in combination with a divided journal-box, e e', having inclined bearing-surfaces e² e⁶ therein, and nut e⁸, substantially as and for the purposes set forth.

3. The arbor C', having journal-bearing formed of plain and conical parts c c', in combination with two-part box e e', the former, e, having sleeve-extension e⁴, and the latter having threaded socket-extension e⁵ and nut e⁸, substantially as set forth.

4. In a holding mechanism for grinding punches, the combination of a rotary power-shaft, a holding-chuck mounted in a journal-bearing having pivoted support on the shaft,

and gear mechanism for imparting rotary motion from the shaft to the chuck, substantially as set forth.

5. The combination of rotary power-shaft B, rotary chuck C, journal-box E, having pivotal support on the shaft, gears b b', and adjusting mechanism for setting and supporting box E and chuck C at the desired angle of elevation, substantially as set forth.

6. The combination of rotary chuck C, journal-box E, having a pivotal support, connecting-rod H, pivoted arm D', and binding or clamping mechanism for securing the arm as against movement on its pivot, substantially as set forth.

7. The combination of rotary chuck C, journal-box E, having pivotal support, two-part connecting-rod H, adjusting-coupling h², pivoted arm D', slotted plate d⁵, and binding-screw d⁶, substantially as set forth.

8. The combination of shaft B, chuck C, journal-box E, having arms E' and collars E², such collars encircling the shaft and movable lengthwise thereon, and gears b b', the latter being connected with the shaft by feather and groove, substantially as set forth.

9. The combination of shaft B, chuck C, journal-box E, having a sliding pivotal support on the shaft, gears b b', bar i, sliding block D, having box d, connected therewith, which encircles the shaft between gear b' and the journal-box support, arm D', pivoted to block D, connecting-rod H, slotted plate d⁵, and binding-screw d⁶, substantially as set forth.

10. The combination of bed-plate N, adjustable plate or frame I, adjusting-screw m, rotary power-shaft B, chuck C, and gears b b', connecting-rod H, pivoted arm D', and clock-spring D³, substantially as set forth.

11. The combination of plate I, rotary shaft B, chuck C, gears b b', and journal-box E, such box having pivotal support on the shaft, which is free to be moved in both rotary and longitudinal directions, substantially as set forth.

12. The combination of bed-plate N, adjustable plate I, screw-rod m, shaft B, journal-box E, having pivotal support on the shaft, chuck C, and gears b b', substantially as set forth.

13. The combination of bed-plate N, sliding plate I, rotary driving-shaft S, counter-shaft R, gears r³ s³, shaft B, gear b⁴, sliding gear r', journal-box E, having pivotal support on shaft B, chuck C, arbor C', and gears b b', substantially as set forth.

14. The combination of shaft B, chuck C, journal-box E, having pivotal support on the shaft, connecting-rod H, pivoted arm and drum D' D², and clock-spring D³, substantially as set forth.

In testimony whereof I have hereunto set my hand.
